AUTOMATIC ENGINE CUT-OFF

Charles R. Guinn, Konawa, Okla.

Application July 31, 1944, Serial No. 547,499

6 Claims. (Cl. 161—7)

The present invention relates to new and useful improvements in devices for automatically interrupting the operation of an internal combustion engine after the same has run for a predetermined length of time.

In many instances, such as in the pumping of an oil well, it is desired to interrupt the operation of the engine after a predetermined lapse of time, and it is accordingly an object of the present invention to provide an apparatus for accomplishing this purpose without depending upon the operator to stop the engine at the desired time.

An important object of the present invention is to provide an apparatus of this character embodying trip means for closing a valve in the fuel line of the engine, together with a fluid collecting chamber for actuating the trip means when a predetermined volume of fluid has been collected in the chamber.

A further object is to provide an apparatus of this character of simple and practical construction, which is efficient and reliable in performance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and wherein:

Figure 1 is a fragmentary sectional view of the crank case of an internal combustion engine showing the automatic cut-off attachment in position thereon.

Figure 2 is a top plan view of the trip mechanism for the cut-off valve.

Figure 3 is a sectional view taken substantially on a line 3—3 of Figure 1.

Figure 4 is a sectional view taken substantially on a line 4—4 of Figure 1.

Figure 5 is a side elevational view of a modified form of the invention.

Figure 6 is a sectional view taken substantially on a line 6—6 of Figure 5.

Referring now to the drawings in detail, and first with respect to the form of the invention illustrated in Figures 1 to 4, inclusive, the numeral 5 designates the crank case of an internal combustion engine of a type employed in oil well pumping, the crank shaft being shown at 6 and the piston rod 7 through the operation of which oil is picked up in the crank case and thrown

in the direction as shown by the arrows in Figure 1 of the drawings.

The present invention comprises an oil collecting container 8 positioned inside the crank case 5 and pivotally supported therein on a pin 9 carried by a bracket 10.

Supported in closely spaced relation above the top of the container is a hood structure 11 including a neck portion 13 in the bottom of which 10 is a horizontal partition 14 closing the bottom portion of the neck, the partition having an opening 15 therein adapted to be closed by a tapering needle-type valve 16 slidably mounted in a spider 17 within the neck and formed with a threaded stem 18 threaded through a bridge structure 19 on the upper end of the neck, the valve being threadedly adjusted by means of a winged head 20.

Projecting outwardly and upwardly from the 20 upper edge of the neck is an oil collecting trough 21 in which oil thrown by the crank shaft is received for draining into the neck 13 and subsequently collected into the container 8 under the control of the valve 16.

25 The container 8 is normally held in its upright position, as shown in Figure 1 of the drawings, by means of a trip mechanism which includes a vertical rod 22 extending upwardly through a bracket 23 secured to the outside of the crank case, the rod being pivotally supported on the bracket 23, as at 23', and the lower end of the rod being connected to the pin 9 by means of links 24 and 25, the container 8 and link 25 being secured to the pin 9 for moving the link 24 and rod 22 in the direction as shown by the arrows in Figure 1 of the drawings, upon a downward tilting movement of the container 8 through the collection of a predetermined volume of oil therein.

40 The upper end of the rod 22 is formed with a horizontal extension 26 having a shallow hook 7 at its outer end engaging a similar hook 28 formed on one end of a trip arm 29, the arm extending angularly from a shaft 30 journaled in bearings 31 supported on the outer end of the bracket 23. The shaft 30 also includes a crank arm 32 overlying a plunger-type valve 33 in the fuel line 34 of the engine.

45 The trip arm 29 is yieldably urged downwardly by means of a coil spring 35 attached to the bracket 23 and extending upwardly therefrom and with its upper end engaging a wire U-shaped member 36 closed at its upper end by a collar 37 through which a screw 38 is threaded for bearing on top of the trip arm 29. The screw 38 is adjust-

ed by means of a winged head 39 to regulate the tension of the spring 35.

In the bottom of the container 8 is a ball valve 40 retained in a cage 41, the ball normally being maintained in its closed position by gravitation and secured to the inside of the crank case 5 is a valve actuating finger 42 disposed in the path of downward movement of the ball 40 when the container 8 is tilted downwardly to open the valve 40 to drain the contents of the container 8 back into the crank case.

In the operation of the device, the valve 33 is normally maintained in an open position to permit fuel to pass through the fuel line 34 for operating the engine when the trip mechanism is set in the position as shown in Figure 1 of the drawings. While the engine is running, oil will be thrown into the trough 21 for subsequent collection in the container 8 and after a predetermined lapse of time sufficient oil will be collected in the container to overcome the intergripping engagement of the hook members 27 and 28 of the upper end of the rod 22 and trip arm 29 and thus through gravitation cause a releasing of the hook members 27 and 28 whereupon the spring 35 will pull the trip arm 29 and valve actuating arm 32 downwardly for closing the valve 33 and thus cut off the fuel line for the engine to interrupt operation thereof.

The downward movement of the container 8 will cause the finger 42 to engage the ball valve 40 to thus open said valve and permit the contents of the container 8 to drain back into the crank case.

The device of the present invention is reset for effective operation by moving the container 8 back to its normal vertical position and again placing the hook members 27 and 28 in engagement with each other, as shown in Figure 1.

In the form of the invention illustrated in Figures 5 and 6 of the drawings, a bracket 43 is provided which is attached to a suitable part of the engine, the bracket having the vertical rod 44 pivotally attached thereto as at 43' for holding the trip arm 45 in its inactive position, as previously explained with reference to the first-mentioned arm 29. The trip arm 45 controls the closing of the valve in the fuel line (not shown) through the means of the coil spring 46 similar to the operation of the first-mentioned spring 35 as explained with respect to Figures 1 to 4, inclusive.

The links 47 and 48 are connected to the lower end of the rod 44, the link 48 being secured to the pivot pin 49 and to which is also secured a cup 50 in which a container 51 is removably supported.

A neck 52 projects upwardly from the container 51 and supported on an upstanding extension 53 of the bracket 43 is an upper container 44 having a pet cock 55 attached to its bottom portion and positioned immediately above the neck 52 for controlling the rate of flow in the draining of liquid from the container 54 into the container 51.

After a predetermined volume of the liquid has been drained into the container 51, the trip arm 45 will be released by the downward tilting movement of the container 51 in the manner as previously explained with reference to the container 8.

Also carried by the bracket 43 is a stop 56 in the path of downward movement of the container 51 to limit movement thereof.

When resetting the mechanism illustrated in

Figures 5 and 6 of the drawings, the contents of the container 51 is emptied back into the upper container 54 and the device is then again made ready for use by moving the container 51 and its support 50 back to normal position and re-engaging the hooked end of the rod 44 and the trip arm 45.

From the foregoing it will be apparent that the device constructed in accordance with the present invention will effectively cut off the fuel for the engine after a predetermined lapse of time.

It is believed that the details of construction, manner of operation and advantages of the device will be readily understood from the foregoing without further detailed explanation.

Having thus described the invention, what I claim is:

1. An automatic engine cut-off comprising a cut-off valve in the fuel line of the engine, a spring-influenced trip mechanism adapted to close the valve, and means for releasably retaining the trip mechanism inactive and comprising a container pivotally mounted in the crank case of the engine and adapted to receive oil splashed by the operation of the engine crank shaft, means for controlling the flow of oil admitted into the container, and latch means connecting the container to the trip mechanism and adapted for releasing the latter by a pivotal movement of the container when the container is supplied with a predetermined volume of oil.

2. An automatic engine cut-off comprising a cut-off valve in the fuel line of the engine, a trip mechanism for actuating the valve and normally governing the valve when opened so as to establish flow in the fuel line, a gravity-actuated liquid-collecting container controlling operation of the trip mechanism, said container being pivotally mounted, disposed in a normally upright position and having a releasable retaining connection with the trip mechanism, and means for selectively supplying a predetermined measured quantity of liquid to said container whereby to load the container to a weight sufficient to cause gravitating movement of the container and thereby a release of the connection with the trip mechanism and a resultant actuation of the cut-off valve which closes the latter so as to stop flow in the fuel line.

3. An automatic engine cut-off comprising a cut-off valve in the fuel line of the engine, a trip mechanism for actuating the valve and normally governing the valve when opened so as to establish flow in the fuel line, a normally positioned, gravity-actuated, liquid container operatively connected to the trip mechanism for controlling actuation thereof and through such connection both the trip mechanism and the container are releasably held each in their respective normal positions, and means for feeding liquid to the container under volume control, whereby, upon loading of the container with liquid to a definite weight, the container moves so as to cause actuation of the trip mechanism which effects the closing of said cut-off valve.

4. An automatic engine cut-off comprising a normally open cut-off valve in the fuel line of the engine, a trip mechanism for actuating the valve and alternately governing the same in opened and closed positions, a normally positioned, gravity-actuated, liquid container operatively connected to the trip mechanism for controlling actuation thereof and through which connection both the trip mechanism and the con-

tainer are releasably held in their respective normal positions, and adjustably regulatable volume control means for feeding liquid in predetermined degree of flow to the container, whereby, upon loading of the container with liquid to a definite weight, the container moves so as to cause actuation of the trip mechanism which effects the closing of said cut-off valve.

5. An automatic engine cut-off comprising a normally open cut-off valve in the fuel line of the engine, a spring-influenced trip mechanism adapted to close the valve and alternately govern the same in opened and closed positions, means for releasably retaining the trip mechanism in its normally set position with the cut-off valve in its opened position, said means comprising a pivotally supported, normally upright, tiltable liquid container, adjustably regulatable volume-control means for feeding liquid to the container

10 in measured quantity and during a definite period of time, and releasable catch means connecting the container to the trip mechanism in the normal position of the container and the normal set position of the trip means, said latch means acting to automatically release the trip mechanism by a tilting movement of the container when the container becomes supplied and loaded to a definite weight with a predetermined volume of liquid.

15 6. An automatic engine cut-off as set forth in claim 5, wherein the container is provided with normally closed drain valve means and associated external means cooperating to open the valve means so as to empty the container when the same, as loaded with liquid, is tilted to a definite angular degree under weight of the contained liquid.

CHARLES R. GUINN.
